UNITED STATES PATENT OFFICE.

G. W. MOFFITT, OF WASHINGTON, PENNSYLVANIA.

IMPROVEMENT IN CAR-COUPINGS.

Specification forming part of Letters Patent No. 33,958, dated December 17, 1861.

To all whom it may concern:

Be it known that I, G. W. MOFFITT, of Washington, in the county of Washington and State of Pennsylvania, have invented a new and useful Improvement in Couplers for Railroad-Cars; and I do hereby declare that the following is a full, clear, and exact description of the construction and operation of the same, reference being had to the accompanying drawings, making a part of this specification, in which—

Figures 1 and 2 are vertical longitudinal sections of two of the said couplers in the positions which they will occupy just previously to the running into contact of the two cars to which the said couplers are supposed to be respectively applied, and Fig. 3 like sections of the same after the cars are connected.

Like letters indicate the same objects when in the different figures.

The object of this invention is to produce a reliable self-locking wrought-iron link-coupler for railroad-cars which will be secure against the loss or displacement of the link.

It consists in constructing, arranging, and combining together within the coupling-box or buffing draw-head, substantially as herein-after described and specified, a wrought-iron link, a catch or hook, and an abutment with a drop-piece, so that in running into contact two cars having the said link, catch, abutment, and drop-piece applied to each the link of either will interlock with the catch or hook of the other, and thus produce a reliable connection of the two cars, the said apparatus allowing of the said connected cars being instantly disconnected at the pleasure of the conductor in charge by his operating a treadle or other sufficient device for the purpose arranged in connection therewith, substantially as herein-after described.

In the drawings, A A' are the links, B B' the catches or hooks, F F' the abutments with their self-acting drop-pieces f'' f'', and G G' the treadles of the two cars, respectively.

The link and hook of each coupler are made of wrought-iron and are secured permanently in the box or buffing draw-head C, so as to project horizontally therefrom by means of a strong wrought-iron bolt D, which is fixed permanently in a vertical position through the rear end of the said box C, the rear ends of

the link A and hook B being loose on the bolt D and arranged so that the link shall lie loosely upon the bottom of the box C and the rear end of the hook be supported above it by means of a cross-pin or suitable shoulders formed on the said bolt D, while its forward or hooked end rests between the sides of the link in a slot in the bottom of the box C upon a strong spring E, which is fixed firmly to the under side of the box by means of a nut d on the bolt. The upper part of the inside of the box C has a cast-iron abutment F, so formed and bolted firmly to it as to project sufficiently forward to form a stop or rest for the upper end of the hook proper, as seen in the drawings, and has jointed to it near its projecting end a drop-piece f'', which rests in a reclining position against the front end of the said hook B when the upper end of the latter is in contact with the abutment F, substantially as shown in the drawings.

The stem of the treadle G is bent laterally, so as to be jointed to the lower part of the front end of the hook B and so as to clear the link, and is supported in a vertical position in front of the platform of the car, so as to project above the latter sufficiently far to enable the conductor of the car to force the hook downward until the upper end of the latter shall be on a level or in the same horizontal plane with the lower part of the inner side of the box C, as occasion may require the disconnection of the cars.

Operation: When two cars which are fitted with my invention approach each other closely, the outer end of the link A of each will be nearly in the same horizontal plane, as seen in Figs. 1 and 2, and as they come in contact one link underruns and lifts the other, so that the outer end of the latter runs over the upper faces of the opposite drop-piece f'' and abutment F, while the underrunning link's bevel end slides up the front side of the opposite hook, and coming thus into contact with the projecting under side of the abutment F forces the said hook downward with its spring E, passes over, and drops down around the vertical part of the said hook, thus completing the connection of the two cars, as seen in Fig. 3, the upper link lying loosely with its forward end upon the abutment of the opposite box. It therefore mat-

ters not which link of the two couplers slips over the hook, as either will perfect the connection required.

To disconnect the cars, the conductor presses downward the treadle G of the hook which holds the connecting-link A, and thus allows the drop-piece f'' to swing downward and hang in a vertical position directly over the hook B', so that on the conductor's removing his foot from the treadle the said hook will be held down with its point on a level or in the same horizontal plane with the bottom of the link which connects with it, as indicated by the dotted lines in Fig. 3, and as the cars are drawn apart the connecting-link A passes freely over the point end of the depressed hook, tripping up the drop-piece f'' and allowing the said hook to return behind the drop to its normal position. It will therefore be seen that the link A or A' cannot be lost or displaced from its box, and that it will always be in position for interlocking with the hook of an opposite coupler of the same kind as the two cars to each of which the same has been applied are run into contact. Another advantage of this self-acting link-coupler arises in the fact that a car to which it has

been applied will connect with a car which has been adapted for using the old removable link and bolt, as the link of my improved coupler will pass into the box or mouth of the draw-head of the old link-coupling, so that it can be connected therewith by its drop-bolt in the usual manner.

Having thus fully described my improved coupler and pointed out its utility, what I claim as new therein of my invention, and desire to secure by Letters Patent, is—

The application of a wrought-iron link A, a hook or catch B, and an abutment F, with a drop-piece f'' , to a buffing draw-head of a car, so that when two cars to which the same are respectively applied are run into contact with each other for the purpose of being coupled the link of either will interlock with the catch or hook of the other, and thus complete a reliable connection of the said cars, the same being constructed and arranged together to operate substantially in the manner described.

G. W. MOFFITT.
